UNITED STATES PATENT OFFICE.

CASS L. KENNICOTT, OF CHICAGO, ILLINOIS.

APPARATUS FOR PURIFYING WATER.

SPECIFICATION forming part of Letters Patent No. 703,596, dated July 1, 1902.

Application filed August 20, 1901. Serial No. 72,665. (No model.)

To all whom it may concern:

Be it known that I, CASS L. KENNICOTT, a citizen of the United States, residing at Chicago, in the county of Cook and State of Illinois, have invented new and useful Improvements in Apparatus for Purifying Water, of which the following is a specification.

My invention relates particularly to water-purifying apparatus of the character described in Patents Nos. 646,108 and 665,606, granted to me, respectively, March 27, 1900, and January 8, 1901.

My primary object is to provide certain improvements, first, in the general arrangement of parts, with a view to preventing dangerous or objectionable freezing; second, in matters of details of construction, with a view to simplicity therein, and, third, in the main soft-water tank, with a view to increasing the capacity thereof.

My invention is illustrated in its preferred form in the accompanying drawings, in which—

Figure 1 represents a view of the apparatus, partly in elevation and partly in section; Fig. 2, an enlarged plan view of the same with the roof and outer tank removed; Fig. 3, a detail view of the water-lift employed; Fig. 4, an enlarged broken vertical section taken as indicated at line 4 of Fig. 2; Fig. 5, a still further enlarged broken section similar to Fig. 4, but showing only a portion thereof; Fig. 6, a plan view of the soda-solution and auxiliary soft-water tanks shown in Fig. 5; Fig. 7, a detail of the float-controlled valve in the soda-solution tank; Fig. 8, an enlarged broken section at the upper portion of the apparatus, taken as indicated at line 8 of Fig. 2 and illustrating the manner of controlling the hard-water supply; Fig. 9, a detail view of the valve controlling the hard-water admission; and Fig. 10 a view similar to Fig. 1, but showing a slight modification of parts.

In the preferred construction, A represents a precipitating-tank having a downtake-conduit A'; A², a mixing pan or trough having communication with the upper end of the conduit A'; B, Figs. 4 to 6, inclusive, a chemical-agent (preferably a solution of soda) tank; B' B², alternately-used sources of supply for the tank B, the tank B being supplied

through a pipe a, receiving its supply alternately through branch pipes a' a², controlled, respectively, by manually-operated valves a³ a⁴; B³, an automatic valve for the pipe a, 55 the same being controlled by a float B⁴, located in the tank B; B⁵ B⁶, chemical (soda) receptacles for the tanks B' B², respectively; B⁷, Figs. 4 and 6, a discharge-pipe for the tank B, having its discharge end located over 60 the pan A²; B⁸, a swinging pipe having connection with the pipe B⁷ on the inside of the tank B and supplied with an inlet-port b, the height of which is automatically regulated by a float in the hard-water tank; C, Fig. 1, 65 a chemical-solution (solution of lime) tank located within the precipitating-tank A and preferably within the conduit A'; C', Fig. 4, a chemical (lime) basket located at the upper end of the tank C and provided with a 70 conduit C^a, leading to the lower end of the tank C; C², a stirrer-shaft journaled in the bracket C³, which supports the shaft through the medium of a collar c; C⁴, a bracket for the lower portion of the stirrer-shaft; C⁵, a 75 stirrer at the lower end of the shaft C²; C⁶, a sludge-discharge pipe for the tank C; C⁷, a gate-valve controlling the pipe C⁶ and having a stem equipped with a rack C⁸, operated by a pinion C⁹ through the medium of a rod 80 C¹⁰, extending to the upper portion of the apparatus; D, Figs. 4 to 6, inclusive, a soft-water tank, affording a source of supply for the lime-basket C'; D', a pipe through which water is delivered from the tank D to the chamber C'; D², a swinging pipe connected with the pipe D' inside the tank D and having an admission-port d; D³, an overflow-pipe located in the tank D, said pipe having an open 85 upper end and its lower end passing through the bottom of the tank D; E, a water-lift wheel having curved hollow arms which dip beneath the surface of the water in the tank A and which communicate with the hollow shaft E', having one closed end E² and communicating at its opposite end with the tank D; F, a motor-chamber having a discharge above the pan A²; F', a water-wheel secured to a shaft F², having bevel-gear connection f with the stirrer-shaft C² and chain connection f' with the water-lift E; G, a hard-water-supply tank having a discharge-orifice g, leading 90

to the water-wheel; G' , a float located within a guide G^2 in the tank G ; H , a frame supporting pulleys h ; H' H^2 , cables connected with the float G' and with the swinging pipes $B^8 D^2$; I , an annular soft-water-storage tank surrounding the tank A and receiving its supply of water through an overflow I' at the upper portion of the precipitating-tank; J , a hard-water-supply pipe connected with a hydrant or other water-supply source and leading to the tank G ; J' , Figs. 8 and 9, an automatically-operated valve controlling the water-admission to the tank G ; J^2 , a float located in a guide J^3 in the upper portion of the precipitating-tank A ; J^4 , link and lever connections between the float J^2 and the valve J' , and J^5 a branch pipe of the pipe J , through which water is supplied to the soda-baskets $B^5 B^6$, said branch pipe being provided with a manually-controlled valve J^6 , Fig. 2, and with a swinging section J^7 , which may be alternately directed to the baskets $B^5 B^6$.

The precipitating-tank A is provided outside the downwardly-flaring conduit A' with the usual perforated baffle-plates k and filter k' , the latter being a short distance below the overflow I' . The tank A is provided with a conical bottom k^2 , having at its center a sludge-outlet controlled by an upwardly-opening valve k^3 , operated by a lever k^4 , pivoted on a support k^5 , connected with the bottom k^2 , the free end of said lever projecting through a slot k^6 in a downward extension k^7 of the casing forming the tank A . The downward extension k^7 is provided with a conical bottom k^8 , and the space between the bottoms $k^2 k^8$ communicates through a pipe k^9 with the sewer. The draw-off pipe C^6 of the tank C extends through the bottom k^2 and communicates with the space beneath the same. Thus it will be seen that the tank C may be flushed independently of the tank A .

Relatively long I-beams K and relatively short I-beams K' , Figs. 2 and 4, support the small tanks and mechanism at the upper portion of the apparatus. A cabin L surmounts the apparatus and incloses the mechanism and such pipes as are exposed above the tank A . The supply-pipe J extends upwardly through the tank A , passing through the baffle-plates k thereof, and is in this manner protected against freezing.

As shown in Fig. 4, the discharge from the pan A^2 is through a chute l to the upper portion of the conduit A' , a shelf or baffle-plate l' being arranged beneath the discharge end of said chute to receive the falling stream. Directly above the baffle-plate l' is a discharge-pipe l^2 for the lime-water tank C . Thus it will be seen that the hard water and soda solution passing through the chute l would be met by the lime-water escaping from the top of the tank C , a thorough mixing being produced at said baffle-plate.

65 The operation will be readily understood from the foregoing description. Hard water

is maintained at a given height in the tank G by the float-controlling valve regulating the admission thereto, and the tanks $B' B^2$ are alternately filled through the branch pipe J^5 and swinging section J^7 thereof. Each of the tanks $B' B^2$ is large enough to hold one day's supply of soda solution. Said soda-solution tanks are alternately drawn upon to supply the tank B , the supply thereto being automatically regulated by the float-controlled valve B^3 . A supply of soft water is maintained at given height in the tank D through the lift-wheel E and overflow D^3 . The swinging pipes $B^8 B^2$ are of sufficient size to conduct more liquid than can enter through the orifices with which said pipes are provided. Consequently the height of liquid above said orifices constitutes the head acting at the discharge for each of tanks B and D . As has been explained, the height of said orifices is regulated by the float G' in the tank G , so that the effective heads of liquid in the tanks B and D vary with the head in the tank G , as has been fully described in my aforesaid patent, No. 665,606. The stirrer C^5 being in constant operation (when the water-wheel is in operation) prevents settling of the lime in the tank C . Moreover, the stirrer C^5 is provided centrally with a spade-like downward projection m , which extends into that portion of the pipe C^6 which lies above the valve C^7 and prevents caking of the lime above said valve. The tank I may be drawn upon at will for a supply of soft water. The tank C , which is of relatively small diameter, is by reason of its location protected against freezing. When it is desired to flush out the tank C to remove the sediments therefrom, this may be accomplished through the medium of the valve C^7 , operated by the rod C^{10} , extending to within convenient reach of the upper portion of the apparatus. The lever K^4 is accessible from the outside of the base of the tank A , and the tank A may be flushed when desired.

In Fig. 10 I have shown the lime-tank C located outside the conduit A' and passing through the filter k' and the upper baffle-plates k . In this construction the positions of the soda-supply tanks $B^5 B^6$ and of their parts are changed somewhat; but the connections are the same. While this construction is a less desirable construction than the one above described, it still possesses the advantage that the tank C is protected against freezing, and the construction is more compact than constructions heretofore used.

Changes in details of construction within the spirit of my invention may be made. What I claim as new, and desire to secure by Letters Patent, is—

1. In water-purifying apparatus, the combination of an annular soft-water tank, inter-communicating precipitating and chemical-solution tanks inclosed by said annular tank, said precipitating-tank having communica-

tion at its upper portion with said annular tank, a vertically-disposed stirrer in said chemical-solution tank, a water-wheel geared to said stirrer and having a discharge leading 5 to the upper portion of said precipitating-tank, and a hard-water-supply source for said water-wheel, substantially as described.

2. In water-purifying apparatus, the combination of a precipitating-tank, a chemical-solution tank within said precipitating-tank, a source of hard-water supply above said precipitating-tank, a stirrer in said chemical-solution tank, a water-wheel geared to said stirrer and operated by the hard water and 15 having a discharge leading to said precipitating-tank, and an overflow for supplying liquid from said chemical-solution tank to said precipitating-tank.

3. In water-purifying apparatus, the combination with a precipitating-tank having a downtake-conduit located therein, of a chemical-solution tank within said conduit, said last-named tank having communication near its upper end with the upper portion of said 25 conduit.

4. In water-purifying apparatus, the combination of a precipitating-tank provided at its bottom with a valved discharge-opening, a chemical-solution tank within said first-named tank, a discharge-passage leading from 30 said last-named tank through a wall of said first-named tank, and a valve controlling the discharge from the lower end of said chemical-solution tank.

35 5. In water-purifying apparatus, the combination of a precipitating-tank provided with a downtake-conduit, a chemical-solution tank located in the upper portion of said conduit and provided near its upper end with an overflow-port, a stirrer within said last-named tank, a stirrer-shaft, a water-wheel, a discharge-passage leading therefrom to the upper portion of said conduit adjacent to said overflow-port, a hard-water-supply source 40 communicating with said water-wheel, and gear connections between said water-wheel and stirrer-shaft.

6. In water-purifying apparatus, the combination of a precipitating-tank provided with 50 a downtake-conduit, a chemical-solution tank within said conduit and provided at its upper end with an overflow-port, a water-supply source for said last-named tank, a water-wheel, a discharge-passage leading therefrom, and communicating with the upper portion of said conduit adjacent to said overflow-port, a chemical-solution tank provided with a discharge-passage communicating with the passage leading from said water-wheel, and a 55 hard-water tank communicating with said water-wheel.

7. In water-purifying apparatus, the combination of a precipitating-tank provided with 60 a downtake-conduit, a lime-water tank located in the upper portion of said conduit and provided with a lime-basket having a dis-

charge-passage leading to the lower portion of said lime-water tank, a soft-water tank located above said precipitating-tank, a water-lift for supplying water thereto from the upper portion of said precipitating-tank, a pipe connecting said soft-water tank with said lime-basket, means for automatically controlling the discharge of water through said pipe, an overflow-port for said lime-water tank opening into the upper portion of said conduit, a soda-solution tank, a supply source therefor, means for automatically regulating the height of liquid in said soda-solution tank, a discharge-pipe for said soda-solution tank, 80 means for automatically regulating the discharge therethrough, a water-wheel, a discharge-passage leading therefrom and communicating with the upper portion of said conduit adjacent to said overflow-port, the 85 discharge from said soda-solution tank passing to the same point, and a hard-water-supply source for said water-wheel.

8. In water-purifying apparatus, the combination with a precipitating-tank, of a lime-water tank within said precipitating-tank provided at its lower end with a discharge-pipe passing through a wall of said precipitating-tank, a valve extending transversely of said pipe, an actuating-rod for said valve having 90 its upper end located at the upper portion of the apparatus, and connections between said rod and valve through the medium of which said valve is operated.

9. In apparatus of the character described, 100 the combination with a precipitating-tank having a downtake-conduit, and provided beneath the lower end of said conduit with a conical bottom, of an inclosed chemical-solution tank having a conical bottom and a pipe 105 leading therefrom and extending through the bottom of said precipitating-tank, a centrally-located valve at the bottom of said precipitating-tank, a valve at the lower end of said chemical-solution tank, and inclosed operating means for said last-named valve extending 110 to the upper portion of the apparatus.

10. In water-purifying apparatus, the combination with a precipitating-tank having a downtake-conduit, of a lime-water tank located in said conduit, a stirrer in said last-named tank, a vertical stirrer-shaft, a water-wheel having a transverse shaft geared to said stirrer-shaft, a water-lift wheel having an axis parallel to said water-wheel shaft geared 120 thereto, a soft-water tank supplied by said water-lift wheel and provided with an overflow, a lime-basket in the upper portion of said lime-water tank, a pipe leading from said soft-water tank to said lime-basket, an overflow-port for said lime-water tank communicating 125 with the upper portion of said conduit, a passage leading from said water-wheel to the upper portion of said conduit adjacent to said overflow-port, a soda-solution tank, a discharge-pipe therefor communicating with said last-named passage, a source of supply 130

for said soda-solution tank, means for automatically regulating the admission therefrom into said soda-solution tank, a hard-water tank at the upper portion of said water-wheel, 5 a supply source therefor, means for maintaining the water in said last-named tank at a given height, a float in said last-named tank, and means connected with said float for au-

tomatically controlling the passage of liquid from said soft-water tank and said soda-solution tank.

CASS L. KENNICOTT.
